UNITED STATES PATENT OFFICE.

FREDERICK K. MAERZ, OF CLEVELAND, OHIO, ASSIGNOR TO BENJAMIN F. KLEIN, DOING BUSINESS AS THE KAYLINE CO., OF CLEVELAND, OHIO.

DESIGN FOR A LAMP SHADE.

Application filed February 25, 1927. Serial No. 20,891. Term of patent 7 years.

To all whom it may concern:

Be it known that I, FREDERICK K. MAERZ, a citizen of the United States, residing at Cleveland, in the county of Cuyahoga and State of Ohio, have invented a new, original, and ornamental Design for Lamp Shades, of which the following is a specification, reference being had to the accompanying drawing, forming part hereof, wherein the figure is a side elevation of a lamp shade, showing my new design.

I claim:—

The ornamental design for a lamp shade, as shown.

FREDERICK K. MAERZ.
